METHOD OF FORMING BUNGS

George W. Lawton, Cincinnati, Ohio, assignor to
The United States Bung Manufacturing Com-
pany, Cincinnati, Ohio, a corporation of New
York

Application March 20, 1941, Serial No. 384,390

2 Claims. (Cl. 144—309)

This invention is concerned with improvements in the method of compressing and tapering wooden bungs for barrels, drums, casks, and the like. My copending application which has now matured into United States Patent No. 2,283,331 is specifically directed to apparatus useful in the practice of the method of the present invention. This same apparatus is illustrated in the drawing forming a part of this application, but only as a representative instrumentality with which the methods of the present invention may be practiced. This application is a continuation in part of the application on which my aforesaid United States Patent No. 2,283,331 issued.

It has long been known that a very effective seal for containers intended to hold liquids, such as barrels or casks, may be formed by inserting a compressed and tapered wooden bung into an opening of corresponding size and shape. This is because the liquid in the container contacting the inner end of the bung will cause it to swell, particularly where the surfaces have been compressed. If not confined by the sides of the opening, the bung would return to its original shape. However, since the swelling takes place while it is confined, the resultant fit of the bung in the opening is a very tight one.

In the practice of methods now in use, a bung blank is first formed from a board of the required diameter, usually by cutting with a hollow-mounted chisel or by sawing. This blank will be circumferentially round and flat on the ends with straight, that is, untapered, sides. In order to compress and taper the sides to form the completely compressed and tapered bung, it is necessary to apply pressure to the sides of the blank. To obtain a taper, pressure must be unequal; that is, progressively greater toward the top or bottom of the blank. In accordance with methods now in use, this is done by the single operation of forcibly jamming the blank into a hollow die, the sides of which are flared outwardly. If the blank survives this operation, it will then be tapered to substantially the degree of inclination of the walls of the die. The blank will then be a completely tapered and compressed bung.

However, the correspondence of the degree of taper of the bung to the degree of inclination of the sides of the die is more theoretical than real. All wood tends to spring back after compression of any sort has been applied. Different woods differ greatly in moisture content, arrangement and strength of fibers, and one lot of the same wood will differ greatly from another. For this

reason, the blanks will tend to spring back unequally after compression, and, in many instances, a bung which has been completely forced into the die will be an unfit commercial product because after removal from the die, its sides will have sprung back to such a degree that it will not fit into the opening for which it is intended. Likewise, a particularly soft blank will be rammed into the base of the die with considerable force, thus compressing and sometimes marring and splitting the end of the bung. The number of culs resulting from this method is very high and constitutes a real problem in the bung industry.

15 It has been the concept of the present invention to provide a method of compressing and tapering a wooden bung blank in which the compression and taper will be applied in a series of comparatively easy stages, as distinguished 20 from the single harsh dieing operation. With this principal end in view, one of the objects of the present invention has been to provide a method of tapering and compressing wooden bung blanks in which the compression will be applied to the sides of the blank only, and not partially to the end as is the case in other methods.

Another object of the invention has been to provide a method of compressing and tapering wooden bung blanks in which the compression 30 will be applied in a series of distinct stages between which the blank will be free from compression so that the wood fibers may spring back to some extent before the next compression is applied.

35 Another object of the invention has been to provide a method of tapering and compressing wooden bung blanks in which it is possible to apply a predetermined degree of taper much more accurately than has been the case with earlier methods.

40 Another object has been to provide a method in which the taper is applied gradually, and the possibility of splitting the wood is to a great extent eliminated.

45 Other and further objects will be apparent from the further and more detailed description of the invention when considered in conjunction with the drawing which illustrates a preferred 50 form of apparatus that is adapted to practice the method of the invention.

In the drawing:

Figure 1 is a front elevation of the apparatus showing a three-unit assembly with the gate closure of two of the units open to illustrate the

passage of the bungs through a continuous passageway.

Figure 2 is an end view of the apparatus.

Figure 3 is a section of line 3—3 of Figure 1.

Figure 4 is a side elevation of a bung blank.

Figure 5 is a side elevation of a bung blank after it has passed through the first stage of compression.

Figure 6 is a side elevation of a bung blank after it has passed through the second stage of compression.

Figure 7 is a side elevation of a completed bung.

In this apparatus, 1 is a base plate which serves as one surface of the blank passageway and to which various of the other elements are attached. The units which are all substantially identical, comprise curved die surfaces having tapered walls 2, revolving rolls 3, and closure means, such as the gate 4. A completely enclosed passageway is formed in each unit between the surface of the base plate 1, the inner surface of the gate or closure member 4, and the side walls of the roll 3 and the die 2. The walls of the roll and die are at the same degree of inclination from the base in each unit, but may be at a greater degree in succeeding units in order to increase the taper applied to the blanks as they progress through the passageway. However, it is not absolutely necessary to provide this progressive degree of inclination.

The roll 3 is fixed upon an end of a shaft journaled within a bearing in the front plate and within a bearing in a rear plate 11 joined to the front plate by cross strips 12. A gear 13 is fixed upon the shaft 10 intermediate of the front and rear plates and preferably is of a diameter to permit its teeth to mesh with a corresponding gear of a second unit to entrain the gears of a series of units, the end gear of the train being in mesh with a driving gear 14 driven from some suitable source of power.

By this method of gear train transmission, the gear 13 of one unit rotates in an alternate direction from that of its next adjoining unit or units which permits the relative positioning of the several units so that the blanks follow a serpentine course as they pass from one unit to another, and no sharp corners which might obstruct their passage are presented at any point in the course.

The blanks 5 are first inserted in the opening 6. In the preferred construction of the apparatus, the walls of the roll and the curved die surfaces in this first unit (not shown) will be spaced apart barely sufficiently for the entrance of the blank. The turning of the roll 3 rotates the blank and, at the same time, compresses it between the inclined walls while it is closely confined between the inner surface of the closure element 4 and the face of the base plate 1. As shown, the bung progresses through the first unit until it reaches a position between the first and second units. At this point, the bung passes between the stationary guide elements 7—7 (one of these is concealed by the gate) where it is out of contact with any roll so that it is no longer under compression. The sides of the passage at this point should be sufficiently large to permit the bung to drop by gravity to the next unit. The same operation is

completed through successive units, but since the walls of the passageway become closer together in each succeeding unit the compression will be increased as the bung progresses. Likewise, since the degree of inclination of the walls of the roll and the curved die surfaces is greater in succeeding units, the degree of taper applied to the bung will be correspondingly increased in the particular apparatus illustrated. When the bung has passed through the terminal unit, it will come out the opening 8.

It will be noted that the apparatus described compresses the bung in a series of more or less gentle compressing operations, as distinguished from the harsh methods now in vogue. It will also be noted that the pressure is applied to the sides only, and that after compression the fibers of the wood are given an opportunity to spring back before further compression is applied.

As illustrated in Figures 4, 5, 6 and 7, the bung blank starts out with sides that are perpendicular to the base plate. As it proceeds the taper is gradually applied and by the same operation the sides are compressed. When it emerges from the passageway, as shown in Figure 7 it is a completely tapered and compressed bung.

Although the apparatus described is useful and effective in practicing the method, there are doubtless other types and kinds of apparatus with which the method could be practiced equally effectively. It may also be practiced by hand; for example, by successively inserting blanks under pressure in a series of dies having side walls of progressive inclination, the dies themselves being of progressively smaller size. Doubtless, other ways of practicing the method will suggest themselves to those skilled in the art.

Having described my invention, I desire to be limited only by the ensuing claims:

1. The method of forming a bung which comprises subjecting a cylindrical wooden blank to a series of tapering operations, applying pressure radially upon the blank in such manner that the blank is converted from a cylindrical form to a frusto-conical form, with the pressure applied upon the blank in each operation remaining uniform throughout that operation but increasing from operation to operation for progressive compression of the blank.

2. The method of forming a bung which comprises subjecting a substantially cylindrical wooden bung blank to a series of individual stages of compression in each of which pressure is applied radially upon the circumference of the blank, the pressure applied upon the circumference of the blank during each stage being greater adjacent one face of the blank than at the other face but remaining uniform throughout each stage, but with the greater pressure successively increasing from stage to stage whereby the frusto-conicality of the blank becomes accentuated as the blank progresses from stage to stage, while the maintenance of the uniform pressure during each stage permits the fibres of the blank to become set before being subjected to the next successive pressure operation.

GEORGE W. LAWTON.
